UNITED STATES PATENT OFFICE

WILLIAM G. MAIER, OF LOS ANGELES, CALIFORNIA

BATHING SUIT

Application filed September 18, 1930. Serial No. 431,780.

The present invention relates to women's bathing suits, and more particularly to a suit of this character having a bust-supporter forming part thereof, with a view of eliminating the necessity of using a separate garment such as a brassière for this purpose.

More specifically stated, the invention comprehends the use of a suitable piece of material of proper size and outline to define 10 breast-receiving pockets when the material is attached to the bust of the waist portion of the suit.

In carrying out the invention I secure the material defining said pockets to the waist 15 portion of the suit in a manner to reinforce the suit or structure in its entirety, and thus provide a strong and substantial bust-supporter as a part of the suit itself.

The nature and advantages of the invention will be better understood when the following detailed description is read in connection with the accompanying drawings, the invention residing in the construction, combination and arrangement of parts as 25 claimed.

In the drawings forming part of this application like numerals of reference indicate similar parts in the several views and wherein:

30 Figure 1 is a rear elevation of a bathing suit embodying the subject matter of the present invention.

Figure 2 is a front elevation.

35 Figure 3 is a sectional view on line 3—3 of Figure 1.

Figure 4 is a detail view of the piece of material utilized to form the bust-supporter when associated with the suit.

40 Referring to the drawings in detail, A indicates generally a woman's bathing suit of any ordinary or well known construction but in accordance with the present invention, the suit has incorporated therein a bust-supporter, which as above stated eliminates the necessity of using a separate garment brassière for this purpose. As clearly illustrated in the drawings, the waist portion of the suit itself is formed or provided with spaced 45 breast-receiving pockets properly located on

the inner side of the front portion of the garment.

In the specific embodiment of the invention herein shown, I make use of a separate piece of material, preferably of the outline 55 shown in Figure 4, and this piece of material is of a length substantially equal to the width of the garment to extend across the entire width of the front portion thereof. The piece of material preferably includes two substantially crescent shaped portions 10 and 11 respectively which are connected by an intermediate relatively narrower portion 12, and it is of course to be understood that the strip may be made from any suitable material and also vary in size and configuration without departing from the inventive idea. This strip or piece of material when arranged against the inner side of the front of the 60 waist portion of the garment, is preferably stitched at its ends to the garment directly beneath the arm openings therein, and also stitched along its lower edge to the garment as at 13, while the intermediate portion 12 is also stitched to the adjacent portion of the 65 garment or suit thereby defining spaced breast-receiving pockets 14 as clearly shown in Figure 3. A short length of tape 15 extends from the lower edge of the intermediate portion 12 to the upper edge of the suit and 70 stitched to these parts along its longitudinal edges as at 16, this tape serving to reinforce the suit in its entirety, and also provides a strong and substantial bust-supporter which 75 will bear its weight without subjecting the suit to any unnecessary or undue strain, and thus preserve the normal outline or shape of the upper portion of the suit.

80 While it is believed that from the foregoing description the nature and advantages of the invention will be readily apparent, I desire to have it understood that I do not limit myself to what is herein illustrated and described, and that such changes may be 85 resorted to when desired as fall within the scope of what is claimed.

88 What I claim as new is:

90 In a bathing suit, a bust-supporter including a piece of material having substantially crescent-shaped end portions and a re- 95

duced intermediate portion, stitching securing the ends of said material and the lower edge thereof to the waist portion of the suit, thereby providing the latter with spaced ⁵ breast-receiving pockets, and a reinforcing tape extending from the neck portion of the suit to the lower edge of the intermediate portion of the material and stitched thereto along its longitudinal edges for the purpose ¹⁰ specified.

In testimony whereof I affix my signature.

WILLIAM G. MAIER.
